TOY FRAME FOR STUFFED TOYS

Abraham Menzin, New York, N. Y.

Application February 23, 1946, Serial No. 649,507

3 Claims. (Cl. 46—151)

1

This invention relates in general to a toy and in particular to a toy frame for a stuffed toy.

It is an object of this invention to provide a new frame for a stuffed toy.

It is another object of the invention to provide a durable wire frame for a stuffed toy.

It is an additional object of the invention to provide a durable adjustable frame for a stuffed toy.

Further objects of the invention as well as the construction and use thereof will in part be obvious and will in part become apparent from the following disclosure.

For further comprehension of the invention, and of the objects and advantages thereof, reference will be had to the following description and accompanying drawings, and to the appended claims in which the various novel features of the invention are more particularly set forth.

In the accompanying drawing forming a material part of this disclosure:

Fig. 1 is a perspective view of a toy frame according to one form of the invention.

Fig. 2 is a perspective view of a toy frame according to another form of the invention.

Fig. 3 is a fragmentary enlarged view of an adjusting means according to one form of the invention, according to one of the frames shown in the previous figures, in cross section taken along the line 3—3.

Referring to the figures in detail there is shown in Fig. 1, a toy frame in the form of a frame for a toy to simulate a child's dog 10, comprising two outer wire members 11 and 12 bent in the outline of a dog, having legs 13, a head 14 and a tail 15, optionally with ears 16 to complete the resemblance to a toy dog.

The two wire members 11 and 12 are substantially identical in shape and size, and are joined together at numerous spaced positions by means of cross members or supports 17. These supports 17 are of substantially equal length so that the two members 11 and 12 are mounted substantially parallel with each other. There is thus provided a toy frame for a simulated dog, having two dog-like outlines mounted apart from each other to form a hollow frame in the shape of a dog.

The wire members 11 and 12, and the support members 17 are constructed of a stiff but flexible metal, such as, an iron or steel wire. The members are thin enough to be bent, and yet are thick enough to retain their relative shape in spite of the hard wear usually given to children's toys. A wire with a diameter of about $\frac{1}{32}$ " up to

about $\frac{1}{8}$ " will be satisfactory, depending on the size of the toy and the conditions of wear and usage.

The supports 17 are securely bound to the wire members 11 and 12, to mount them to the members and to mount the members together. For this purpose a strong bond is necessary to prevent accidental separation, and in the presently preferred embodiment of the invention these supports are secured by welding or the like. Soldering with the present commercial solders is avoided, since these do not have the rugged structural characteristics which are necessary for the structure.

15 Optionally at several key points in the structure of the frame; namely, the tip of the tail, ears, nose, feet and the like, there is provided a strengthened support 17^a, for example a support of substantial increased thickness. This ensured 20 increased strength at the critical points in the structure.

Toward the center of the body of the toy frame are a plurality of adjustable supports 17^b which are adapted to be lengthened to cause a thickening 25 in the body of the toy. Except for these adjustable supports the body is of substantially even thickness, and accordingly the adjustable portion of the frame gives ability to create a more lifelike appearance at will. For example, the 30 central portion of the body of the toy may be stuffed to an enlarged shape to simulate a well fed, fat, animal. Alternatively the body may be left in its original substantially flat shape to simulate the sleek type of animal.

The structure of these adjustable supports 17^b according to one form of the invention is set forth in Fig. 3. This support 17^b comprises a male member 21 mounted, for example on member 12 and a mating female member 20 mounted on the other member 11. The male member 21 has a series of forwardly extending prongs or teeth 22 which mesh with a series of forwardly extending teeth 23 on the inside of the female member 20, so that the male and female members resist 45 forces tending to close the two members together. As shown in Fig. 3, these two members 20 and 21 may be so constructed that they cannot be closed together; alternatively the male member may be sufficiently smaller than the female member so that the members may be closed together by separating the teeth and carefully passing the one member past the other, while a simple closing motion will be resisted by meeting teeth.

50 According to this form of the invention, there-

fore, there is provided a toy frame capable of being stretched in one general location only, to simulate in appearance a fat animal, but which under normal use will substantially remain flat.

In Fig. 2 there is shown another embodiment of the invention comprising a toy frame 10 in the form of a cat, comprising two outer members 11 and 12 to simulate the outline of a cat and having a head 14, feet 13, a tail 15, ears 16 as in the previous form of the invention. This frame likewise has cross supports 17, 17^a, and 17^b as in the form of the invention shown in Fig. 1. The adjustable feature of the toy as shown in Fig. 3 is valuable with this form of the invention as with the previous form.

The toy frame as illustrated in any of the forms of the invention is provided with a suitable decorative covering, such as, a cloth or other fabric designed in imitation of the animal represented by the shape of the frame. The covered frame is stuffed, for example with hair, cotton, or other fibrous or similar stuffing material to produce a complete toy animal. Decorative features such as eyes, mouth, and the like may be added.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a toy frame having two like frame members parallelly connected together by spaced groups of supports, means between the spaced groups of supports adjustably connecting together the frame members to be expanded between the spaced groups of supports, comprising a female member mounted at one end of one of said frame members and having its other end extended toward the other frame member, a male member mounted at one end on the other frame member and having its free end slidably extended into said female member, and cooperating teeth formed on said female member and said male member for holding said male and female members in various extended positions to similarly space the frame members.

2. In a toy frame having two like frame members parallelly connected together by spaced

groups of supports, means between the spaced groups of supports adjustably connecting together the frame members to be expanded between the spaced groups of supports, comprising a female member mounted at one end on one of said frame members and having its other end extended toward the other frame member, a male member mounted at one end on the other frame member and having its free end slidably extended into said female member, and cooperating teeth formed on said female member and said male member for holding said male and female members in various extended positions to similarly space the frame members, said teeth being of the ratchet type and extended to permit free extension of said male and female members but to resist collapse thereof.

3. In a toy frame having two like frame members parallelly connected together by spaced groups of supports, means between the spaced groups of supports adjustably connecting together the frame members to be expanded between the spaced groups of supports, comprising a female member mounted at one end on one of said frame members and having its other end extended toward the other frame member, a male member mounted at one end on the other frame member and having its free end slidably extended into said female member, and cooperating teeth formed on said female member and said male member for holding said male and female members in various extended positions to similarly space the frame members, said teeth being of the ratchet type and extended to permit free extension of said male and female members but to resist collapse thereof, said female member having slits extended in from the end thereof into which said male member extends permitting expansion of said female member so that said teeth will ride over one another when said male and female members are extended.

ABRAHAM MENZIN.
